UNITED STATES PATENT OFFICE.

LESLIE R. McDONALD, OF MONTREAL, QUEBEC, CANADA.

DISPLAY APPARATUS.

Application filed August 1, 1925. Serial No. 47,486.

My invention relates to that class of display apparatuses wherein flexible placards are wound around a rotatable placard holder, movable step by step, and are successively released to unroll and drop into view position.

The objects of my invention are to simplify the arrangement and construction of the operative parts of the mechanism; to provide means for preventing confusion in the operation of the mechanism in case any placards are omitted from their normal positions in the placard carrier; to provide means for overcoming adhesions to the roll by the last placard, due to static electricity or other similar causes; and to provide means whereby the movement of the placard carrier may be automatically arrested after a predetermined cycle of operation; and to secure these objects by the use of improved and novel mechanism as I will now proceed to explain.

In the drawings, Fig. 1 is a side view of mechanism embodying my improvements, the case in which it is mounted being broken away; Fig. 2 is a front view of the operative mechanism taken on the line 2—2 of Figs. 1 and 3, looking to the left, the case being omitted and the view being shortened by the omission of medial parts; Fig. 3 is a sectional elevation taken on the line 3—3 of Fig. 2, looking to the right, and also showing diagrammatically the electric motor and circuit for the cut-off switch mechanism; Fig. 4 is a detached plan view of the switch; and Fig. 5 is a sectional view taken on the line 5—5 of Fig. 3, looking to the left; and Fig. 6 is a detail of one end of the placard carrier taken as on the line 6—6 of Fig. 2, looking to the left. Figs. 2 to 6, inclusive, are on an enlarged scale as compared with Fig. 1.

In all the figures similar parts are designated by corresponding reference numerals.

In the case 1 is mounted a suitable frame 2—2, in which the operative mechanism is assembled.

An electric motor 3, through a sprocket 4 and a link belt 5, drives a sprocket 6 turning on a shaft 7 and carrying with it gears 8 and 9.

Gear 8 meshes with a gear 10 on a shaft 11 journalled in the frame of the apparatus and carrying the lifting rollers 12—12, which operate to raise the free end of the rearmost placard at the proper time.

The gear 8 also meshes with a gear 14 on a shaft 15 journalled in the frame 2—2 and carrying a number of sheet agitators 16, 16 attached thereto. These agitators are preferably of a polygonal form; and the shaft 15 is so positioned in the frame 2—2 that the foremost placard carried by the placard carrier hangs over and against the agitators, and will be shaken by them, because of their irregular contours, as the shaft 15 revolves.

The gear 9 meshes with a gear 18 mounted on a shaft 19 journalled in the frame 2—2 and carrying on its inner end an eccentric 20, the primary function of which is to oscillate and cause the step by step rotation of the placard carrier. The placard carrier embodies a shaft 22 carried by arms 23, 24 supported by a rod 25, the ends of which rest in slots 26, 26 in the upper edge of the frame 2—2.

On the shaft 22 are assembled the placard carrier heads 30, 31, and an intermediate placard supporting disk 32. The head 30 is provided with a series of holes 33, 33, to support one end of the placard rods 34, which extend in a series around the carrier, all but one, however, being omitted from Fig. 2 for clearness.

A keeper disk 35 is pivoted on the rod 22 and is provided with a series of holes 36, 36 adapted to register with the holes 33 in the head 30. A slot 37 in the disk 35, through which passes a set screw 38, permits the keeper disk to be rotated so that its holes 36, 36 may be thrown into or out of registration with the holes 33, 33 in the head 30. The head 31 is also provided with a series of holes 40, 40, the outer ends of which are smaller than their inner ends, which are adapted to receive the ends of the rods 34, 34, but not to allow them to pass through the head 31.

This arrangement allows the rods to be slid through the keeper disk 35, and head 30 and into the head 31, and to be locked in place by the rotation of the keeper disk 35, secured by the set screw 38. At the same time it permits any rod to be removed when the keeper disk 35 and the head 30 are in proper registration, by inserting a pin or similar instrument in the small end of the hole 40, and thereby pushing the rod 34 out so that it can be withdrawn from the heads. It should be understood that the rod passes through a loop at one end of the placard.

The arm 24 is provided with an adjustable

extension 42 swinging on a pin 43, one end of which projects through the arm toward the head 31. By means of a slot 44 and a set screw 45 adjustments can be made between the extension 42 and the arm 24. A roller 46 is pivoted near one end of the extension 42, and travels against the cam 20 on the shaft 19.

A dog 50 registers between teeth 51, 51 on the periphery of the head 31 to prevent anti-clockwise movement of the carrier head.

On the shaft 22 is mounted another arm 53, one end of which, 54, lies in front of the pin 43 which, therefore, limits the backward swing of the end 54 of the arm 53.

The arm 53 carries a pawl 55 pivoted thereto, and being held to duty by gravity, against the teeth 51, 51, on the head 31. A stop pin 56, adjustably mounted in a slot 57 in the end of the frame 2, intercepts the path of the arm 53, and by adjustment of this pin the range of movement of the arm 53 may be regulated.

It will be seen, therefore, that as the cam 20 revolves, the placard roll, carried by the swinging arms 23 and 24, will tend to swing back so that the roller 46 follows the cam 20, thereby swinging the placard carrier forward and back as the cam revolves, a complete backward swing of the carrier permitting the rearmost placard to come in contact with the rollers 12 on shaft 11, which are revolving anti-clockwise, and hence will raise the placard up and push it forward over the carrier permitting it to drop into view position. Each swing of the placard carrier will cause the pawl 55 to turn the head 31 one tooth, so that the placards will be successively presented to the raising rollers 12-12.

In practice, however, it may be desirable or necessary to leave out one or more placards, thereby causing breaks in the series. If a placard is omitted, however, when the carrier turns so that the omitted placard should register against the raising rollers 12-12, those rollers will engage with the next succeeding placard, and thereby throw it forward one step in advance of its proper time, with the result that the mechanism will be thrown out of proper step, and disarrangement of the placards and mechanism will ensue.

To guard against this I provide means for preventing the placard carrier from swinging quite back to the raising rollers, at a time when an omitted placard's position is before those rollers. The means which I employ are these. In the head 31 I place a second series of holes 60, 60, adapted to receive a pin or pins 61; and in the frame of the machine I mount a stop 62 which is shown as having a forked end 63 straddling a set bolt 64 slidably placed in a slot 65 in the frame 2. If a placard is omitted from any position in the placard carrier, a pin 61 is

placed in a hole 60, complementary to the hole 40 from which the placard has been omitted, the end of the pin 61 projecting out so as to be intercepted by the stop 62. When, therefore, the placard carrier swings back, the pin 61 will encounter the stop 62, before the placard roll comes in contact with the rollers 12-12, so that on that particular backward swing of the placard roll no placard will be raised and thrown forward over the roller into view position.

It is necessary, however, that the proper step by step rotation of the placard carrier should not be interrupted, and this is provided for by the use of the floating pawl 55, the range of action of which is limited by the pins 43 and 56 so that it will turn the placard carrier the proper step even though the placard carrier does not complete its full backward swing.

It sometimes happens that because of the accumulation of static electricity in the placard roll, or for other causes, the placards will tend to stick to each other or to the glass front of the case, so that the proper falling forward into view position of each successive placard will be interfered with. To overcome this difficulty I make use of the agitators 16, 16, which lie behind the placard as it drops forward, and, by shaking it, assist in overcoming any tendency to adhere or stick to the placard roll or to the case. In practice I find that this very satisfactorily overcomes the difficulties above mentioned.

In apparatuses of this description, which are placed in public places and are intended to operate without constant supervision, it is desirable to provide means whereby the movement of the apparatus may be automatically suspended at a predetermined time.

To accomplish this I have devised the following means. In the frame of the machine I mount two toothed disks 70, 71, turning on a pivot 72 and pressed into frictional contact by suitable means such as a spring 73. One of these disks, for instance 70, has one tooth less than the disk 71. The disk 70 has a socket notch 74 in its edge and the disk 71 has a similar notch 75 in its edge. An arm 76 is pivoted as at 77 in the frame 2 and carries a roller 78 pressed to duty on the cam 20 by a spring 79.

This arm 76 carries a pawl 80 which engages with the teeth on the disks 70 and 71; so that at each revolution of the cam 20, the pawl 80 will be thrown down against the teeth to an extent governed by the position of the stop 81. Hence at each complete revolution of the disks, their relative positions will be displaced one tooth; so that they will have to revolve such a number of times as is represented by the product of the number of teeth on one disk multi-

plied by the number of teeth on the other before they will regain their previous relative positions. The time necessary for this can be governed by the speed at which the 5 apparatus is operated.

An arm 82 is mounted on a pivot as at 83, and is urged toward the disks 70 and 71 by suitable means such as a spring 84 stretched between one end of the arm 82 and a suitable anchorage in the frame. This arm 82 10 has a flange 85 extending across the edges of the disks 70 and 71, and normally resting thereagainst. The arm 82 is connected as through a link 86 with a switch 87 placed 15 in a circuit 90, 91, 92, which includes the motor 3.

So long as the flange 85 is held up by the flanges on the disks 70 and 71, the circuit, including the motor, will remain closed, and the 20 mechanism will continue to operate. But if the slots 74 and 75 register opposite to the flange 85, that flange will pass up into them, thereby raising the arm 82, opening the switch 87, breaking the circuit and stopping 25 the operation of the apparatus.

To start the apparatus the flange 85 may be withdrawn from the notches 74 and 75, and the switch 87 closed by suitable means. In the drawings I have shown the 30 key 87' mounted on a handle 88, by turning which the arm 82 may be pressed down so as to close the switch 87. The contour of the key is such as to make it normally retain the position shown in Fig. 3 under the pressure 35 of the arm 82 against it. Means such as a trip 89 on the flange of disk 70 may be employed to turn the key into a neutral position as the disks revolve, and to thereby allow the arm 82 to move its flange 85 into contact 40 with the edges of the disks 70 and 71.

By means of my improvements I obtain an apparatus from which one or more placards may be omitted without interfering with the normal operation of the mechanism; in which the tendency of the placards to stick to the roll or case is overcome; and in which means are provided for automatically arresting the movement of the mechanism at predetermined points in its operation; and I accomplish this with a simple 45 and efficient mechanism which will operate with marked dependability.

It will be understood that the particular embodiment of my improvements which I 50 have illustrated and described is to be considered as a typical and not an exclusive form. For details of construction may be modified by the use of mechanical equivalents and the like without departing from 55 the spirit of my invention as described and claimed.

Having thus described my invention, what I claim and desire to secure by Letters Patent of the United States is:—

65 1. In a display apparatus, the combination

of rotating means and a rotatable placard carrier, a series of flexible placards each attached by one end thereto and partially rolled thereupon with their free ends depending therefrom, means for lifting the depending portions of the placards, successively, and means for optionally temporarily interrupting the operative action of the lifting means, while the placard carrier is rotating. 70 75

2. In a display apparatus, the combination of rotating means and a rotatable placard carrier, a series of flexible placards each attached by one end thereto and partially rolled thereupon with their free ends depending therefrom, means for lifting the depending portions of the placards, successively, and means for optionally preventing the operative action of the lifting means at a predetermined sheet position. 80 85

3. In a display apparatus, the combination of rotating means and a rotatable placard carrier, a series of flexible placards each attached by one end thereto and partially rolled thereupon with their free ends depending therefrom, intermittently cooperating means for lifting the depending portions of the placards, successively, and means for optionally preventing the operative action of the lifting means at a predetermined 90 95 sheet position.

4. In a display apparatus, the combination of rotating means and a rotatable placard carrier, a series of flexible placards each attached by one end thereto and partially rolled thereupon with their free ends depending therefrom, means for lifting the depending portions of the placards, successively, and means for optionally suspending the operative action of the lifting means at any 100 105 predetermined sheet position and automatically permitting the resumption of such operative action at a subsequent sheet position.

5. In a display apparatus, the combination of rotating means and a shiftable and step by step rotatable placard carrier, a series of flexible placards each attached by one end thereto and partially rolled thereupon with their free ends depending therefrom, means for lifting the depending portions of the placards successively, means for moving the placard carrier into the field of operation of the lifting means at each step of rotation, and optionally operable means for arresting the movement of the carrier short of such 110 115 field of operation. 120

6. In a display apparatus, the combination of rotating means and placard carrier swinging means, a swingable and rotatable placard carrier, a series of flexible placards each attached by one end thereto and partially rolled thereupon with their free ends depending therefrom, means for lifting the depending portions of the placards successively, and means, embodying adjustable stops, 125 130

- for limiting the swing of the placard carrier and thereby optionally preventing the operative action of the lifting means.
7. In a display apparatus, the combination of placard carrier rotating means, including a ratchet wheel and a cooperating, floating pawl, a rotatable placard carrier, a series of flexible placards each attached by one end thereto and partially rolled thereupon with their free ends depending therefrom, means for lifting the depending portions of the placards successively, and means for optionally preventing the operative action of the lifting means.
8. In a display apparatus, the combination of rotating means and a rotatable placard carrier, a series of flexible placards each attached by one end thereto and partially rolled thereupon with their free ends depending therefrom, means for causing the placards successively to fall forward over the placard carrier toward view position, and means for producing irregular waves in the placard and thereby overcoming adhesion of a free portion of the placard to the placard roll.
9. In a display apparatus, the combination of rotating means and a rotatable placard carrier, a series of flexible placards each attached by one end thereto and partially rolled thereupon with their free ends depending therefrom, means for causing the placards successively to fall forward over the placard carrier toward view position, and agitating means for producing waves in the intermediate portion of a placard and thereby overcoming adhesion of the free portion of the placard to the placard roll.
10. In a display apparatus, the combination of rotating means and a rotatable placard carrier, a series of flexible placards each attached by one end thereto and partially rolled thereupon with their free ends depending therefrom, means for causing the placards successively to fall forward over the placard carrier toward view position, and agitating means, embodying rotatable, polygonal elements, for overcoming adhesion of the free portion of the placard to the placard roll.
11. In a display apparatus, the combination of rotating means and a rotatable placard carrier, a series of flexible placards each

attached by one end thereto and partially rolled thereupon with their free ends depending therefrom, means for causing the placards successively to fall forward over the placard carrier toward view position, and rotatable elements irregularly striking the back of the placard, intermediate of its ends, for overcoming the clinging effect of frictionally produced electricity in the placard.

12. In a display apparatus, the combination of rotating means and a rotatable placard carrier, a series of flexible placards each attached by one end thereto and partially rolled thereupon with their free ends depending therefrom, means for lifting the depending portions of the placards, successively, a plurality of elements successively engaging with the placard and constituting placard agitating means, common means for actuating the carrier, the lifting means and the agitating means, and means for optionally preventing the operative action of the lifting means.

13. In a display apparatus, the combination of rotating means and a swingable and rotatable placard carrier, a series of flexible placards each attached by one end thereto and partially rolled thereupon with their free ends depending therefrom, means for lifting the depending portions of the placards successively, placard agitating means, common means for swinging and rotating the carrier, and actuating the lifting means and the agitating means, and means for optionally preventing the operative action of the lifting means.

14. In a display apparatus, the combination of rotating means and a swingable and rotatable placard carrier, a series of flexible placards each attached by one end thereto and partially rolled thereupon with their free ends depending therefrom, means for lifting the depending portions of the placards successively, placard agitating means, common means for swinging and rotating the carrier and actuating the lifting means and the agitating means, means for optionally preventing the operative action of the lifting means, and automatic means, actuated by the carrier swinging means, for arresting the movement of the apparatus.

LESLIE R. McDONALD.
